UNITED STATES PATENT OFFICE.

JAMES SALZ, OF NEW YORK, N. Y., ASSIGNOR, BY MESNE ASSIGNMENTS, TO PENCIL PRODUCTS CORPORATION, OF NEW YORK, N. Y., A CORPORATION OF VIRGINIA.

HARD-RUBBER PENCIL.

1,414,752.

Specification of Letters Patent. Patented May 2, 1922.

Application filed November 27, 1920. Serial No. 426,692.

To all whom it may concern:

Be it known that I, JAMES SALZ, a citizen of the United States, residing in the city, county, and State of New York, have invented certain new and useful Improvements in Hard-Rubber Pencils, of which the following is a specification.

This invention relates to mechanical magazine pencils of the thin lead type and 10 the object is to produce such a pencil that is neat in appearance, simple in construction, and yet so cheap to manufacture that is can be sold for a fraction of a dollar. The invention primarily consists in adding 15 a metallic lead propelling mechanism to a non-metallic composition body and making use of the adhesion between the metal and the composition to hold the parts together. The body being of some easily 20 moldable material, such as hard rubber, so that the parts which make up the body can be molded or extruded and the propelling mechanism inserted into the body and the body parts assembled with a minimum of 25 labor used in cutting, fitting and soldering as is the case with metal pencils.

My invention is capable of embodiment in many different forms and, while I shall 30 illustrate it by the best embodiment there- of known to me, such embodiment is to be regarded as only typical of many possible embodiments, and my invention is not to be confined thereto.

Speaking more particularly, I have de- 35 vised a central body or barrel portion which is formed with a central opening which may or may not be threaded, and surround- 40 ing the central opening are a plurality of lead receiving apertures or ducts extending through this barrel portion. Into the central aperture of the barrel portion I insert by drive fit a metallic lead propelling mechanism which preferably extends beyond the barrel portion at each end. At 45 the lower end a tapered closure cap is screwed on to the projecting end of the propelling mechanism to form the writing end of the pencil, and an erasure bearing closure is forced over the projecting end of the lead 50 propelling mechanism at the top of the barrel portion whereby the parts are held together.

The embodiment herein described is illus-

trated in the accompanying drawings, in which—

Figure 1 is a plan view or elevation of my improved pencil,

Figure 2 is a sectional view taken along the central line of the pencil,

Figure 3 is a sectional view of the molded 60 barrel portion,

Figure 4 is a transverse sectional view taken along the lines 4—4 of Figure 2,

Figure 5 is an elevation of the lead pro- 65 pelling mechanism,

Figure 6 is a side view of the lead pro- 70 pelling mechanism, and

Figure 7 is an elevation of the lead pro- 75 pelling plunger with its head in place.

Fig. 8 shows a modified form of construc- 80 tion.

In the drawings, the numeral 11 repre- 75 sents the formed barrel portion, prefer- 80 ably made from material such as hard rubber, but which may be made of other mold- 85 able materials. This barrel portion has a central aperture 12 extending therethrough which may or may not be internally threaded at 13. It is desirable to have the thread stop at 14, leaving the shoulder. Surround- 90 ing the central aperture 12 lie lead receiving ducts 15 extending the entire length of the barrel portion. 16 and 17 represent the upper and lower ends of the barrel portion which are preferably concave. In the 95 event it is not desired to thread the central aperture 12, as at 13, a metallic sleeve or tube 12^a may be forced into the aperture and this sleeve will carry the internal threads 13 instead of the rubber body 11. In other words, if it is found undesirable to use rubber threads (13 in Fig. 2) there can be substituted therefor, metal threads (13 in Fig. 8).

The lead propelling mechanism includes a 95 metallic sleeve 20 having side slots 21 and 22 and a flange 23 at its lower extremity. Slidably held within the sleeve 20 is a lead propelling plunger 24 adapted to have se- 100 cured thereto a flat head 25 provided with teeth 26 thereon, adapted to mesh with the threads 13 in the barrel portion 11.

Encircling the lead propelling plunger 24 and forced into the unthreaded end 12 of the barrel portion 11 is a nozzle member having 105 an enlarged threaded portion 26' and a

nozzle portion 27. Adapted to be screwed on to the threaded portion 26' is a tapered closure cap 28 formed of hard rubber or other such composition adapted to terminate 5 in a metallic combined lead gripping and tip reinforcing nose 29, which nose is provided with one or more slots 30. 31 represents the lead in the pencil. The top of the pencil is closed by a member 32 also formed 10 of hard rubber or other such composition adapted to be irremovably forced on to the end of the lead propelling mechanism 20 where it projects from the barrel portion 11. 33 represents an eraser frictionally held in 15 a cavity 34 in the end member 32. The lead propelling mechanism extends into an aperture in the closure 32 so that the eraser 33 has not only the function of an eraser but closes that aperture. It is noted that the 20 ends of the closure members 32 and 28 are convexed to be complementary with the concavities of the barrel portion 11. Near each end of the body or barrel portion, I provide on the periphery of the pencil, a plurality of, 25 or a set of ribs 35 and 36 extending in a direction transversely of the pencil. These ribs are preferably undulating and preferably do not extend beyond the maximum periphery of the pencil. These grip devices 30 or ribs are to render more easy the gripping of the pencil, and therefore, I especially place one set of these ribs (35) adjacent to the joint between the cap or tip 28 and the barrel 11, or where the writer's fingers 35 are most likely to come and whereby the writer may more firmly press the pencil against the paper. This also prevents any undue longitudinal movement of the pencil within the writer's hand and at the same 40 time renders more easy the gripping of the writing tip to rotate it or unscrew it from the pencil. The other set of ribs (36) is placed adjacent to the closure member 32 and is to render more easy the gripping of 45 the closure member to rotate it to operate the lead propelling mechanism.

In operation the lead propelling mechanism 20 is inserted into the barrel portion 11 from the bottom, and rotated until the 50 top thereof projects from the barrel portion and the flange 23 seats itself against the threads 13 at 14. The closure end 32 is then irremovably forced on to the projecting end of the propelling mechanism, whereupon the 55 body portion, the closure cap or tip, and the propelling mechanism are all securely held or embedded in place. Next, the nozzle member 27 is screwed or forced into the lower part of the central aperture 12 of the 60 barrel member 11 until it takes the position shown in Figure 2. The leads 31 are then

placed in the magazine apertures of ducts 15 and one lead is placed in the propelling mechanism. Then the writing end 28 which is equipped with screw threads 35^a is screwed into place upon the threaded enlargement 26' of the nozzle member. Rotation of the end 32 expels the lead 31, as required, but when it wears out the tip 28 is removed, one of the leads in the magazine 15 removed therefrom and inserted in the propelling mechanism, the tip 28 then being screwed in place.

I am aware that non-metallic bodies have been used for pencils, namely wood and ivory, combined with metal lead-propelling means, but I have aimed to obtain by a drive-fit an adhering, gripping, cleaving, or clinging quality between the metal and the body not possible with ivory where a smooth surface is presented nor with wood which is liable to split and moreover offers no gripping or clinging action. I have found however, after long experimentation that by availing myself of the affinity between rubber and metal in making either or all of the body, cap and tip of my pencil of rubber, I obtain not only a tight fit between the metal parts and the rubber but a gripping, adhering or clinging action peculiar to rubber and its equivalent compositions such as bakelite or redmanol, which assures an immovable relation between the composition and the metal parts without additional securing means. That is, mere frictional contact between the parts is not sufficient—adhesion being necessary.

What I claim is:

1. A pencil having a rubber body, and a metallic lead propelling means supported in said body by a drive-fit and the clinging quality of the rubber for the metal.

2. A pencil having a body, metallic lead propelling means, and a composition closure for said body attached to the propelling means by drive-fit and the clinging quality of the composition for the metal.

3. A pencil having a body, metallic lead propelling means, a composition tapered writing tip for said body, and a metallic reinforcement for said tip attached to said tip by drive-fit and the clinging quality of the composition for the metal, said reinforcement preventing chipping of the material of said tip.

4. A pencil having a molded composition body having molded therein a plurality of spaced reserve lead compartments.

In testimony whereof I have affixed my signature to this specification.

JAMES SALZ.
